US00D809811S

(12) **United States Design Patent** (10) Patent No.: **US D809,811 S**
(45) Date of Patent: **** Feb. 13, 2018**

(54) **AIRCRAFT SEATS**

(71) Applicant: **Priestman Goode Limited**, London (GB)

(72) Inventors: **Nicholas Moyes**, London (GB); **Michael Davies**, London (GB); **Nigel Goode**, London (GB)

(73) Assignee: **Priestman Goode Limited**, London (GB)

(**) Term: **15 Years**

(21) Appl. No.: **29/575,484**

(22) Filed: **Aug. 25, 2016**

(30) **Foreign Application Priority Data**

Feb. 25, 2016 (EM) 003002047-0001

(51) LOC (11) Cl. **06-01**

(52) U.S. Cl.

USPC **D6/356**

(58) **Field of Classification Search**
